UNITED STATES PATENT OFFICE

145,495

DESIGN FOR A LAPEL WATCH FRAME

David Taylor, Great Neck, N. Y.

Application September 21, 1945, Serial No. 122,230

Term of patent 7 years

(Cl. D42—8)

To all whom it may concern:

Be it known that I, David Taylor, a citizen of the United States of America and a resident of Great Neck, county of Nassau, and State of New York, have invented a new, original, and ornamental Design for a Lapel Watch Frame, of which the following is a specification, reference being had to the accompanying drawing, forming a part thereof.

On the drawing:

Figure 1 is a front view in elevation of a lapel watch frame showing my new design.

Figure 2 is a front view in elevation of the lapel watch frame shown in Figure 1 with parts un-assembled.

Figure 3 is a forward end view in elevation of the lapel watch frame shown in Figures 1 and 2.

The rear of the lapel watch frame is substantially plain.

I claim:

The ornamental design for a lapel watch frame, as shown and described.

DAVID TAYLOR.
